Attorneys.

UNITED STATES PATENT OFFICE.

JOSEPH E. RUATTI, OF LOS ANGELES, CALIFORNIA, ASSIGNOR OF ONE-FOURTH TO
BENJAMIN TORNAVACCA, OF LOS ANGELES, CALIFORNIA.

BRUSH.

Application filed January 5, 1926. Serial No. 79,342.

My invention is a brush adapted to be contained within a casing or holder and to be drawn thereout and attached to the outside of the holder.

An object of my invention is the construction of a brush adapted to be contained in a casing or holder, the brush being readily withdrawn from the holder and secured thereto on the outside, the holder thus forming a handle for the brush.

Another object of my invention is to form a brush with swivelled bristle holders so that the bristles may project at right angles to the brush member or may be folded snugly against the holder. A feature of this construction is in mounting the brush in a holder or casing of relatively small size and allowing the further object of having a reversible brush with two separate sets of bristles.

In the construction of my brush I utilize a rectangular type of casing holder with the brush supporting structure slidable therein; the brush elements having bristles are swivelly mounted in the brush supporting structure and by means of a sliding bar on the side of the brush supporting elements the bristles may be swivelled to extend outwardly at substantially right angles or to lie flat. The brush supporting structure is connected to a sliding head which cannot be completely removed from the holder but allows the brush supporting structure to be withdrawn from the holder and swivelled sidewise to secure the holder in place on the container which forms a handle element. The brush may also be swung from one side of this handle element to the other forming a reversible brush.

My invention will be more readily understood from the following description and drawings, in which:

Figure 1 is a plan of my brush when housed with the casing partly broken away.

Fig. 2 is a longitudinal section on the line 2-2 of Fig. 1, in the direction of the arrows.

Fig. 3 is a longitudinal view on the line 3-3 of Fig. 1, in the direction of the arrows.

Fig. 4 is a view with the brush in opera-

tive position, the brush elements being withdrawn from the casing and secured thereto.

Fig. 5 is a cross section of Fig. 1, on the line 5-5, in the direction of the arrows.

Fig. 6 is a cross section of Fig. 4, on the line 6-6 in the direction of the arrows.

Fig. 7 is a perspective view of the casing with the brush housed therein.

Fig. 8 is an enlarged perspective detail of the inner end of the brush holder, showing the sliding head with the type of double swivel mounting for the brush holder.

Fig. 9 is a detail perspective view partly broken away, illustrating the manner of attaching the swivelled brushes.

Fig. 10 is a detail perspective view illustrating the latch for locking the brush holder to the casing in operative position.

In the drawings, the casing for containing the brush is designated generally by the numeral 1, having top and bottom walls 2, side walls 3, an end wall 4, the other end 5 being open but having inwardly extending cross flanges 6. The side walls are preferably bulged inwardly, forming a resistance or spring element to hold the brush holder in position. The casing also has a pair of slots 7 extending inwardly from the open end 5 and the top and bottom of the casing. Apertures 8 are also formed in the top and bottom of the casing adjacent the closed end 4 to engage the latch as hereunder set forth.

The brush holder comprises side panels 9 having an end piece 10 adjoining them. The free ends 11 are disconnected, but in the closed position a sliding head 12 fits between these ends. A double pivot designated generally by the numeral 13 connects the sliding head to the side panels. This pivot comprises outer links 14 pivotally mounted on the side panels adjacent their free ends. A pair of brackets 15 are secured to the sliding head and a pair of short links 16 are pivoted between the brackets and the outer links 14.

The brush holder has a plurality of bristle holders 17 mounted in journals 18 in the opposite side panels. These bristle holders are preferably constructed in the form of channels as clearly indicated by the nu-

meral 19 in Figs. 3 and 4, the bristles 20 being secured in these channels. The bristles on contiguous bristle holding channels are preferably staggered so that when 5 in the folded position as shown in Fig. 1, the bristles will overlap and hence form a compact brush when folded.

A central partition 21 extends longitudinally of the side panels dividing these into 10 upper and lower halves, each half housing a folding brush with swivelled bristle holders as above described. Each of the bristle holders for the upper and lower brushes are provided with operating arms 22 having 15 a yoke 22'; these arms being rigidly secured to the bristle holders outside of the side panels. The operating arms of the top brush extend downwardly on one side of the brush holder as indicated in Fig. 2, and 20 the operating arms of the lower brush extend upwardly as indicated in Fig. 3 on the opposite side of the brush holder.

A pair of sliding bars 23 shown in the 25 form of channels having a web 24 and flanges 25, are mounted on the outside of the side panels, being secured thereto by pins 26 and 27 sliding in slots 28 and 29 respectively. These pins have an enlarged head on the outside, firmly holding the sliding 30 bars or channels in position. These channels are similar on opposite sides of the brush holder.

A series of pins 30 are secured on the 35 inner side of the channels, being secured to the web and extending into the yokes 22' of the operating arms 22; this construction being the same on opposite sides of the brush holder.

A latch 31 is secured to the brush holder 40 adjacent the end piece 10 of the brush holder. This latch comprises a shaft 32 as clearly illustrated in Fig. 10, journaled in the opposite side panels 9 and having fingers 33 secured to the end of the shaft, these fingers 45 having hooks 34 at their ends. The fingers are so positioned that they form a right angle between the fingers. Coiled springs 35 are secured to the shaft and bear against the end piece 10, there being two of these 50 springs oppositely positioned so that the latch is maintained in its normal position as shown in Figs. 2 and 10. A finger notch 36 is formed on the end piece 10 to allow gripping of the finger to draw the brush out of 55 the casing and a leaf spring 36' is mounted in the casing on the closed end 4, being adapted to bear against the sliding head 12 as clearly shown in Fig. 1.

The manner of utilizing my brush is substantially as follows:

Presuming that the brush is housed in the casing as shown in Figs. 1, 2, 3 and 8, the end piece 10 would be gripped by the fingers or the casing may be given a slight jolt so 65 as to project the end of the brush slightly

out of the casing so that the end piece may be readily gripped. As the brush holder is drawn out of the casing the sliding head 12 is drawn from the position adjacent the closed end 4 to the open end 5 of the casing until it engages the flanges 6 which prevent its further motion. The brush holder may then be swung downwardly 70 through the action of the double pivot 13 or upwardly and positioned on either the top 75 or bottom of the casing as clearly shown in Figs. 4, 6 and 9. In this action the outer link 14 allows the free ends of the side panels 9 to swing past the end of the top and bottom of the casing, such link fitting in the 80 slots 7 as shown in Figs. 4 and 9. The latch 31 is then turned so that the hooks 34 extend through the apertures 8 and thus lock the brush holder to the outside of the casing.

Each of the side bars 23 has a cut-out section 40 on the end of the flange 25 at the end adjacent the double pivot 13 so that the end of the flange as indicated by the numeral 41 will engage the outer link 14 when it swings downwardly into the position shown in Fig. 4. One of the links 14 therefore causes the movement of the side bar of one side while the opposite link will move 90 into the cut-out section 40, thereby leaving the side bar stationary on the other side of 95 the brush.

In the manner of operating the brush as illustrated in the drawings, the bristles which were in the upper portion of the casing as shown in Figs. 2 and 3, are in the 100 lowermost position as shown in Fig. 4 and turned outwardly by the interaction of the operating arms 22 having the yokes 22' co-acting with the pins 30.

The opposite ends of the side bars have a 105 cut-out section 42 on one of the flanges so that the end 43 of the other flange will engage one of the fingers 33 of the latch and move it into the position shown in Fig. 4, 110 engaging in the apertures 8 on the outside of the casing. Thus it will be seen that the movement of pulling the brush out of the casing and swinging it to one side or the other on the outside face of the casing automatically swivels the bristles from a folded 115 to an outstanding position ready for use, and that the sliding side bar also locks the bristles in this position by engaging the outer link 14 and one of the fingers 33.

In constructing my brush it is preferable 120 to have it made with two different types of brush surfaces having different types of bristles or closer set bristles on one side than the other. Therefore on reversing the brush holder to the opposite side of the casing and folding the one set of brush elements in position, another type of brush may be utilized, this change being quickly accomplished.

It is also apparent that changes may be 125 made in the general construction or specific 130

details of my brush without departing from the spirit of my invention as set forth in the description, drawings and claims.

Having described my invention, what I claim is:

1. A brush comprising in combination a hollow casing, a brush holder slideable therein and loosely connected to the inside of the casing, and means to secure the brush holder to one of the outer faces of the casing.

2. A brush holder comprising in combination a hollow casing, a brush holder having bristles secured thereto slideable in said casing, means engaging the inside of the casing to prevent detachment of the brush holder therefrom but to allow positioning the brush holder on one side of the casing, and means to secure said brush holder against one face of the casing.

3. A brush comprising in combination a hollow casing open at one end, a brush holder having bristles secured thereto, an element pivotally connected to the brush holder adapted to slide in the interior of the casing, means in the casing to prevent removal of said element and a holding device connected from said element to the brush holder, adapted to support one end of the brush holder on one of the faces of the casing.

4. A brush as claimed in claim 3, having in addition a pivoted latch secured to the brush holder adapted to support the other end of said holder on the outside of the casing.

5. A brush comprising in combination a hollow casing open at one end, a brush holder having side panels and an end piece, a sliding head positioned between the free ends of the panels, a pivotal connection between the panels and the sliding head, means in the casing to prevent removal of the sliding head through the open end, the said pivotal connection allowing the side panels to be positioned against one of the outside faces of the casing.

6. A brush as claimed in claim 5, in which the pivotal connection comprises double links, one link being connected to the outer

panel, the other link being connected to the sliding head.

7. A brush as claimed in claim 5 in which the brush holder is provided with a plurality of pivotally mounted bristle holders and bristles in said holders.

8. A brush as claimed in claim 5, in which the pivotally mounted bristle holders are mounted in the side panels, bristles in said holders and slideable means mounted on the side panels to partially rotate said holders.

9. In a brush, a substantially rectangular hollow casing open at one end, the said casing having slots adjacent the open end in one of the faces, a brush holder having side panels, a slideable head connected to the free end of said side panels, a double link between said side panels and sliding head, the said link being adapted to fit in the said slots when the brush holder is withdrawn from the casing and cooperative means between the sliding head and the casing to restrain complete removal of the sliding head.

10. In a brush holder, a hollow casing, a brush holder slidably mounted therein, means pivotally connecting the brush holder and casing to permit the brush holder to swing against one of the outside faces of the casing, the casing having an aperture and the brush holder having a latch comprising a shaft, fingers secured to the end of said shaft, said fingers having hooks adapted to fit in the said aperture.

11. In a brush holder a hollow casing, a brush holder slidably mounted therein, oscillating bristle holders having bristles mounted in the brush holder, a sliding bar on the brush holder adapted to operate the said bristles, a link operatively connected to part of the brush holder, adapted to secure said holder against one face of the casing when drawn outwardly, said link being adapted to move the sliding bar and hence oscillate the bristle holders and bristles.

In testimony whereof I have signed my name to this specification.

JOSEPH B. RUATTI.
